UNITED STATES PATENT OFFICE.

EDWIN WILLIAM ROGERS AND THEODORE C. RIEBE, OF CHICAGO, ILLINOIS, ASSIGNORS
TO ROGERS MOTOR LOCK COMPANY, OF CHICAGO, ILLINOIS, A CORPORATION OF
ILLINOIS.

AUTOMOBILE-LOCK.

1,238,945.

Specification of Letters Patent.

Patented Sept. 4, 1917.

Application filed November 4, 1916. Serial No. 129,487.

To all whom it may concern:

Be it known that we, EDWIN WILLIAM ROGERS and THEODORE C. RIEBE, citizens of the United States, and residents of Chicago, 5 in the county of Cook and State of Illinois, have invented certain new and useful Improvements in Automobile-Locks, of which the following is a specification.

Our invention relates to locking devices 10 for automobiles and has particular reference to an improvement upon the construction disclosed in the patent to Conley, 1181571, of May 2, 1916 and Rogers & Rogers, 1182586 of May 9, 1916.

15 One of the objects of the present construction is to provide a device which shall combine the elements of security against tampering, simplicity and compactness. The present structure presents one feature not 20 possessed by either of the devices shown in the patents heretofore referred to; that is, the feature of simultaneously locking the motive fluid and interrupting the supply of electrical fluid for ignition purposes.

25 In order to provide a locking device which shall be in effect impregnable to ordinary attacks, it is essential that all the parts constituting the operating means shall be confined within a casing which is itself 30 locked. In the present device the casing has a removable wall which is held in its proper position by locking mechanism operable in unison with the means for locking the valve controlling the supply of motive 35 fluid to the automobile engine. A construction such as referred to is covered broadly in the patent to Rogers & Rogers heretofore referred to, but the specific form here disclosed is of value because of its simplicity.

40 In order to simplify the mechanism and to provide for ease of assembling, we prefer to mount the lock, the valve-operating member, the electrical contact piece and the spring for controlling the parts all on the 45 removable wall of the casing. In that manner the assembling is facilitated. As a means for locking the removable wall in the casing, we provide cooperating hooks and lugs on the valve-operating member and 50 the casing, the hooks and lugs being in engagement when the parts are in valve-locking position.

One of the principal advantages in the present construction is in that there is no

connection whatever between the lock itself 55 and the pawl or dog which serves to retain the motor valve in locked position. The lock has the function merely of tripping the pawl, there being no positive connection, nor, in fact, any connection when the parts 60 are in locked position.

A further advantage which is gained by the present construction is in that the parts may be unlocked by the motor driver and the key returned to the driver's pocket, it 65 being unnecessary to again insert the key in the lock when the parts are moved to closed position; in fact, the lock does not function at all during that operation. In short, the whole function of the lock which is controlled by the key is to trip the parts. Therefore, effective tampering with the lock 70 is difficult.

The invention will be more readily understood by reference to the accompanying 75 drawings, wherein

Figure 1 is a face view of a locking device constructed in accordance with our invention;

Fig. 2 is a similar view in the absence of 80 the removable end wall of the casing;

Fig. 3 is a similar view with all the operating parts removed;

Fig. 4 is a sectional view on the line 4-4 85 of Fig. 2;

Fig. 5 is a view from the back of the device, the parts being shown in the position they assume in valve-unlocking position;

Fig. 6 is a similar view showing the parts 90 in locked position;

Fig. 7 is a similar view showing the parts in the position they will assume as the pawl is about to be tripped to permit of the return of the parts to the position of Fig. 5, 95 and

Fig. 8 is a vertical sectional view on the line 8-8 of Fig. 2.

Referring more particularly to the drawings, it will be seen that the device contemplates the employment of a casing 10, having a removable front wall 11, the face of which is normally flush with the marginal edge of the casing. As a means for normally holding the removable wall in position, we provide the flanged nut 12. A 100 valve-operating shaft 13 terminates in the casing, this shaft being preferably of the flexible type and being inclosed within an

armored flexible tube 14. At the lower end, the shaft is intended to control the operation of a suitable valve, whereby the supply of motive fluid to the engine may be discontinued. At its upper end, the shaft is engaged by an arm 15, having a hub and a fastening screw for engagement with the shaft. Inasmuch as the construction of the valve at the lower end of the shaft 10 templates the employment of a spring which tends to elongate the flexible shaft 13, and inasmuch as it is essential in the installation of the device to provide for angular adjustment of the arm 15 relative to the shaft, I 15 provide in the upper end of the shaft a peripheral groove 16, with which a key 17 engages. By this means the set screw carried by the arm 15 may be loosened and the arm adjusted without danger of the shaft 20 13 being pulled away from the arm.

A lock is mounted axially of the casing within the removable wall 11. The lock casing, indicated at 18, contains the parts of a Yale lock and acts as the support and 25 center of rotation for a shaft-operating member 19. This member is in the form of a plate and is best shown in elevation in Fig. 2. Projecting from the upper edge thereof is an arm 20, adapted to be manually 30 engaged. Projecting laterally in the opposite direction and from the diametrically opposite portion of the plate is a fork 21, which engages the bent end of the arm 15. Also projecting laterally from opposite sides 35 of the plate at a point substantially ninety degrees from the arms 20, 21, are hooks 22, 23, adapted, when the plate is in locking position, to lie behind lugs 24, 25, respectively, best shown in Figs. 3 and 6. The 40 plate 19 is held in suitable position with relation to the lock casing and the removable wall by clamping nuts 26.

A pair of contact pieces having wire-engaging terminals 27, 28, are secured through 45 suitable insulating material to the bracket 29, best shown in Fig. 8. A contact piece 30, which serves to make an electrical connection between the two contacts is mounted through insulation on a lateral extension 31 50 from the plate 19 and is, therefore, movable in unison with the plate and with the valve-operating shaft.

Pivoted at 32 on the plate 19 is a pawl, the point 33 of which is adapted to engage 55 behind a stop 34, best shown in Fig. 2, formed as a part of the casing. The opposite end of the pawl curves around the spring casing and is engaged by a coil spring 35, the opposite end of which is likewise 60 connected to the plate 19. It will be seen, therefore, that as the parts, as viewed in Fig. 5, are moved clockwise under the action of the lever 20, the pawl will be caused to engage with the stop and lock the parts in

proper position. In this position the valve 65 for interrupting the supply of motive fluid will be in closed position while the contact piece 30 will be out of engagement with the two contacts. By the use of only the parts which have been heretofore described, the 70 motor might be securely locked, but it could not be unlocked.

In order to unlock the parts and to cause the supply of electrical fluid to be continued, we provide on the lock barrel 36 a two-armed 75 member 37. The arm 38 acts merely as a stop for contact with the pin 39, carried by the lock casing. The arm 40, however, has a laterally-projecting portion 41, which is adapted to contact the bent end of the pawl 80 and to lift the point 33 thereof out of engagement with the stop. A strong coil spring is mounted around the lock casing, one end of the spring engaging with the arm 40, as indicated at 42, and the other 85 end 43 of the spring engaging the fork 21. It will be seen, therefore, that as the key is turned to move the arm 40 to pawl-tripping position, the spring which we have indicated at 44 is further energized in order to insure 90 that the valve-opening action shall be complete. After the parts have been released and have snapped to the position of Fig. 5, the lock barrel is returned to normal position under the action of the spring 44, when 95 the key may be removed. It is, therefore, only necessary to manually move the lever 20 to secure the parts in valve-locking position.

The construction here disclosed is, of 100 course, capable of much modification, and such modifications as would readily suggest themselves to those skilled in the art are considered as within the scope of the appended claims.

We claim:

1. In a locking device, the combination of a casing, a valve-operating shaft which terminates in said casing, a lock having a casing, a plate mounted for rotation about said lock casing, a shaft-operating lever, an electric contact piece and a dog all carried by said plate, an actuating lever carried by the lock barrel and a spring connecting said actuating lever and said plate, substantially 115 as described.

2. In a device of the class described, the combination of a casing, a valve-operating shaft in said casing, a lock barrel, an operating member rotatable about said barrel as 120 an axis, a shaft-operating projection on said member, a locking dog on said member, an arm secured to and projecting laterally from said lock barrel and adapted to actuate said dog, and spring means tending to hold said 125 parts in valve-unlocking position, substantially as described.

3. In a device of the class described, the

- combination of a cylindrical casing having an open end, a shaft terminating in said casing, a removable closure for the open end of said casing, a lock carried by said closure, 5 a valve-operating member rotatable about said lock, a pawl pivoted on said operating member, a pawl tripping lever connected to the lock, and spring means tending to hold said parts in valve-unlocking position.
- 10 4. In a device of the class described, the combination of a cylindrical casing having an open end, a closure for said open end, a lock, a valve-operating member rotatable about said lock, an electrical contact piece 15 rotatable with said valve-operating member, and spring means for holding said valve-operating member in valve unlocking position, said lock, operating member, contact piece and spring being secured to and removable from the casing with said closure, substantially as described.
5. In a device of the class described, the combination of a casing having an open end, a closure for said open end, a valve-operating shaft terminating in said casing, a pair 25 of electrical contacts within the casing, a lock and a shaft-operating device secured to and removable with said closure, and locking means for securing said closure in said casing, said locking means being operative when said valve-operating mechanism is in closed position, substantially as described.
- 30 6. In an automobile locking device, the combination of a casing, a removable wall for said casing, a valve-operating shaft terminating in the casing, a shaft-operating member, a lock projecting through said removable wall, a pawl carried by said valve-operating member and adapted to engage a portion of the casing to hold the parts in locked position, and means operable by the lock for disengaging said pawl from its locking position, substantially as described.
- 35 7. In an automobile locking device, the combination of a casing, a removable wall for said casing, a valve-operating shaft terminating in the casing, a shaft-operating member, a lock, a pawl operatively engaging said valve-operating member to hold the 40 same in valve-closing position, and means operable by the lock for freeing said pawl and permitting movement of said valve-operating member to valve-opening position, substantially as described.
- 45 55 8. In an automobile locking device, the combination of a casing, a removable wall for said casing, a valve-operating shaft terminating in the casing, a shaft-operating member, a lock, a pawl carried by said valve-operating member and adapted to engage a portion of the casing to hold the parts in locked position, and means operable by the lock for disengaging said pawl from its locking position.
- 60 9. In an automobile locking device, the combination of a casing, a removable wall for said casing, a valve-operating shaft terminating in the casing, a shaft-operating member, a lock projecting through said removable wall, a pawl carried by said valve-operating member and adapted to engage a portion of the casing to hold the parts in locked position, means operable by the lock for disengaging said pawl from its locking position, and an electrical contact piece operable in unison with said valve-operating member.
- 65 10. In an automobile locking device, the combination of a casing, a removable wall for said casing, a valve-operating shaft terminating in the casing, a shaft-operating member, a lock, a spring engaging said member, a lever projecting outside of said casing and adapted to be manually operated to move said valve-operating shaft to valve-locking position against the resistance of said spring, and means operable by the lock for tripping said shaft-operating member and permitting said spring to move the same to valve-opening position, substantially as described.
- 70 11. In an automobile locking device, the combination of a casing, a removable wall for said casing, a valve-operating shaft terminating in the casing, a shaft-operating member, a lock projecting through said removable wall, a pawl carried by said valve-operating member and adapted to engage a stop to hold said member in locked position, and means operable by the lock for disengaging said pawl from the stop, said pawl and lock being out of operative engagement when the valve-operating member is in locked position.
